(57) **CLAIM**

The ornamental design for a self-balancing vehicle as shown and described.

DESCRIPTION

FIG. 1 is a first perspective view of a self-balancing vehicle;

FIG. 2 is a back view thereof;

FIG. 3 is a front view thereof;

FIG. 4 is a top view thereof;

FIG. 5 is a bottom view thereof;

FIG. 6 is a left view thereof; and,

FIG. 7 is a right view thereof.

The broken lines in the drawings depict portions of the self-balancing vehicle that form no part of the claimed design.
